UNITED STATES PATENT OFFICE.

KIPLING ARTHUR GRANT, FRANCIS ROBERT HALLIDAY, AND ALEXANDER WILLIAM CAMERON, OF TORONTO, ONTARIO, CANADA; SAID HALLIDAY AND SAID CAMERON ASSIGNORS TO SAID GRANT.

IMITATION TREE.

Application filed January 3, 1927. Serial No. 158,645.

It is usual at the Christmas season to use evergreen trees for decorating dwellings and for the supporting of decorations and gifts. These trees, especially in large cities, are 5 comparatively difficult to obtain as well as being somewhat expensive and have to be discarded after they have served their purpose for the season, and the following year a new tree purchased. This, in the course 10 of time, involves considerable expense.

The real tree is also objectionable on account of the falling of the needles, which are very difficult to sweep up.

Our object, therefore, is to devise an imitation tree, which may be folded for storing and used year after year, and which at the same time will have a sufficiently good appearance, particularly when decorated, to take the place of a real tree, and which will 20 at the same time have sufficient strength to support gifts of moderate weight.

We attain our object by means of the constructions hereinafter described and illustrated in the accompanying drawings in 25 which.

Fig. 1 is an elevation of a tree constructed in accordance with our invention;

Fig. 2 an elevation of the upper part of the tree with the top section partly folded; 30 Fig. 3 a plan view of the stack of blank sheets showing the method of gumming the sheets together to form the branch sections of the tree;

Fig. 4 an enlarged detail illustrating the 35 method of connecting the inner edges of the sheets together to provide room for the trunk; and

Fig. 5 a similar view of the sheets in folded position.

In the drawings like numerals of reference indicate corresponding parts in the different figures.

1 is a base, which may be of any suitable form and material and is provided with a 45 socket to receive the post which represents the trunk of the tree. The post will preferably be formed in sections 2, 3 and 4 which may be detachably connected in any convenient manner. The lowermost section 2 will preferably be of thicker material than the upper sections, thus forming a shoulder to support a disk 5 which acts as a support for the lower end of the sections 6 and 7 which represent the branches of the tree.

These sections 6 and 7 are constructed as 55 follows. A plurality of sheets of tough but flexible paper are cut of similar size and are placed one on top of the other in the manner illustrated in Fig. 3. It will be noted that one half of the sheets are gummed on 60 lines 8, while the other half of the sheets, which are arranged alternately with the first mentioned sheets are gummed along lines 9. From this arrangement it follows that each sheet is gummed to its adjacent 65 sheet on one side on lines intermediate the lines on which it is gummed to the adjacent sheet at the opposite side.

To avoid a waste of paper, the stack of 70 sheets is cut on a jagged diagonal line 10, one half of the stack forming the lower section 6 and the other half the upper section 7. It will be noted, however, that the gumming does not extend quite to the jagged line, thus leaving the sheets free of one 75 another at the edges.

The sheets in each section are secured together by hinge strips 11, which as will be seen from Figs. 4 and 5 are folded to form 80 long pleats 12, alternated with short pleats 13. The long pleats 12 are, however, stitched so that they cannot open. To one side of each long pleat is gummed one sheet of paper and to the other side another sheet of paper, and so on until all the sheets have 85 been secured in place.

Preferably, for stiffening purposes, the two outer sheets 14 will be stiff sheets of cardboard.

The hinge strips and sheets having been 90 secured together, it will be evident that the sheets may lie flat on one another as shown in Fig. 5 or opened out as shown in Fig. 4, and when in opened-out position, owing to the opening up of the small pleats 13, a 95 central aperture is provided to receive the post sections 3 and 4.

As, during the opening-up operation, the lower ends of the sheets of the upper section are drawn upwardly and the upper ends of the sheets of the lower section are drawn downwardly, to avoid the formation of a conspicuous joint between the sections, the lower end of the upper section is inclined upwardly from the outer edges of the sheets to the centre of the section, as will be seen from Figs. 2 and 3, and thus the outer edges of the sheets when the sec- 100 105

tion is opened out will extend sufficiently below the upper edge of the lower section to hide the joint.

In order to carry out the realistic effect 5 as much as possible, the gumming lines, as will be seen from Fig. 3, are gradually spaced further apart from top to bottom, thus giving the effect of closer spacing of the branches towards the top of the tree.

10 Various combinations in the shades of paper may be employed if desired for the purpose of improving the effect.

Tie strings 15, or other suitable fasteners will be employed for securing the stiff leaves 15 to one another when the sections are opened out.

From the above description it will be seen that we have devised an imitation tree which will be lasting, clean in use, and which will 20 have a sufficiently realistic effect to take the place of a real tree. The tree will also be sufficiently strong to carry ornaments and to also support gifts of moderate weight in its pockets when the latter are opened up.

25 What we claim is:

1. In an imitation tree, the combination of a central post; and a collapsible body portion adapted to surround said post and shaped to form when opened up the rough 30 outline of a tree, said body portion being formed of a plurality of superimposed sections, each section comprising a plurality of sheets of thin flexible material hingedly connected at one edge, each sheet being secured 35 to its adjacent sheet on one side on lines alternating with the lines on which it is secured to the adjacent sheet on the opposite side, said securing lines extending in a direction away from the axis on which the 40 sheets are hinged, the bottom of said upper section extending in an inclined downwardly direction away from the post.

2. In an imitation tree, the combination of a central post; a collapsible body portion 45 adapted to surround said post and shaped to form when opened up the rough outline of a tree, the said body portion comprising a plurality of sheets of thin flexible material; and a hinge member connecting said sheets, 50 said hinge member comprising an endless band folded to form short pleats and long pleats alternately arranged, the long pleats being secured to prevent their opening, the inner edges of said sheets being secured to 55 said long pleats, said short pleats, when the body portion is opened up, being adapted to open up to provide an aperture for receiving the pole, each sheet being secured to its adjacent sheet on one side on lines alternating 60 with the lines on which it is secured to adjacent sheet on the opposite side, said

securing lines extending in a direction away from the axis on which the sheets are hinged.

3. In an imitation tree, the combination of a central post; and a collapsible body portion adapted to surround said post and shaped to form, when opened up, the rough outline of a tree, said body portion comprising a plurality of sheets of thin flexible material hingedly connected at one edge, 70 said hinge connections being arranged so that the hinged edges of the sheets when the body is opened up, will be spaced from one another, each sheet being secured to its adjacent sheet on one side on lines alternating with the lines on which it is secured to the adjacent sheet on the opposite side, said securing lines extending in a direction away from the axis on which the sheets are hinged. 80

4. In an imitation tree, the combination of a central post; and a collapsible body portion adapted to surround said post and shaped to form when opened up the rough outline of a tree, said body portion comprising a plurality of sheets of thin flexible material hingedly connected at one edge, hinge means, said sheets being secured to said hinge means, said hinge means being pleated between the points of connection of the sheets, 90 each sheet being also secured to its adjacent sheet on one side on lines alternating with the lines on which it is secured to the adjacent sheet on the opposite side, said securing lines extending in a direction away from the axis on which the sheets are hinged. 95

5. In an imitation tree, the combination of a central post; and a collapsible body portion adapted to surround said post and shaped to form, when opened up, the rough outline of a tree, said body portion comprising a plurality of superimposed sections, each section comprising a plurality of sheets of thin flexible material hingedly connected at one edge, said hinge connections being arranged so that the hinged edges of the sheets when the body is opened up, will be spaced from one another, each sheet being secured to its adjacent sheet on one side on lines alternating with the lines on which it is secured to the adjacent sheet on the opposite side, said securing lines extending in a direction away from the axis on which the sheets are hinged. 100
